PULL

Carl J. Dargene, Rockford, Ill., assignor to Amerock Corporation, a corporation of Illinois

Application June 11, 1954, Serial No. 30,945

Term of patent 14 years

(Cl. D10—8)

Fig. 1 is a front elevation of a pull embodying my new design.

Fig. 2 is a side view of the pull.

Fig. 3 is a top view.

Fig. 4 is a sectional view taken along the line 4—4 in Fig. 1.

Fig. 5 is a sectional view taken along the line 5—5 in Fig. 3 and showing the handle portion of the pull in broken lines.

I claim:

The ornamental design for a pull, substantially as shown.
